UNITED STATES PATENT OFFICE

139,363

DESIGN FOR A SUIT OR SIMILAR ARTICLE

Sam Wieder, New York, N. Y.

Application September 29, 1944, Serial No. 115,509

Term of patent 3½ years

(Cl. D3—4)

To all whom it may concern:

Be it known that I, Sam Wieder, a citizen of the United States of America, residing in New York city, county of New York, and State of New York, have invented a new, original, and ornamental Design, for a Suit or Similar Article, of which the following is a specification, reference being had to the accompanying drawing, forming part thereof, wherein,

I claim:

The ornamental design for a suit or similar article, substantially as shown.

SAM WIEDER.
